(57) **CLAIM**

The ornamental design for a laboratory reactor, as shown and described.

DESCRIPTION

FIG. 1 is a front perspective view of the laboratory reactor; FIG. 2 is a left side elevation view of the FIG. 1 reactor; FIG. 3 is a front elevation view of the FIG. 1 reactor; FIG. 4 is a right side elevation view of the FIG. 1 reactor; FIG. 5 is a rear elevation view of the FIG. 1 reactor; FIG. 6 is a top plan view of the FIG. 1 reactor; and, FIG. 7 is a bottom plan view of the FIG. 1 reactor. Broken lining shows features of the laboratory reactor that are not considered to be part of the design.
